UNITED STATES PATENT OFFICE.

ROLLA C. CARPENTER, OF ITHACA, NEW YORK.

STEAM-BOILER.

SPECIFICATION forming part of Letters Patent No. 595,042, dated December 7, 1897.

Application filed March 25, 1896. Serial No. 584,785. (No model.)

To all whom it may concern:

Be it known that I, ROLLA C. CARPENTER, a citizen of the United States, residing at Ithaca, in the county of Tompkins and State 5 of New York, have invented certain new and useful Improvements in Steam-Boilers; and I do hereby declare the following to be a full, clear, and exact description of the invention, such as will enable others skilled in the art to which it appertains to make and use the same.

My invention relates to headers of sectional steam-boilers, and particularly to headers constructed of tough and strong metal, such as 15 wrought-iron or mild steel, and which consequently must be made by some process other than that of casting; and my invention consists in the novel form and construction of the header. 20 The object of my invention is to provide a header for sectional steam-boilers, which may be constructed from wrought-iron or mild steel and by a process other than that of casting, which may be constructed readily and cheaply 25 without the aid of special tools, which is simple in form, and which may be readily connected with the steam-drum of the boiler without the use of special connecting-nipples. This object is attained in the header for sectional steam-boilers herein described and illustrated in the drawings which accompany and 30 form a part of this application, in which the same reference-numerals indicate the same or corresponding parts and in which—

35 Figure 1 is an elevation of a sectional steam-boiler of the inclined water-tube type, employing headers constructed in accordance with my invention, one side of the brick setting having been removed to show the headers in place and to show the manner of their connection with the steam-drum. Fig. 2 is an end view of the boiler of Fig. 1, the end of the brick setting having been removed to show the arrangement of the headers. Figs. 40 3, 4, 5, and 6 are detail views of the header, Fig. 3 being a central longitudinal section thereof, Fig. 4 a front view of a portion thereof opposite the end of one of the generating-tubes and showing the hand-hole by which 45 access may be gained to the generating-tubes, Fig. 5 a transverse section of the header in its upper or round part, taken on the line X X

of Fig. 3, and Fig. 6 a transverse section of the header in its lower or flat part, taken on the line Y Y of Fig. 3; and Fig. 7 is an end elevation of another type of sectional steam-boiler particularly adapted for marine use and employing bent headers and cross generating-tubes, the headers being constructed in accordance with my invention. In this figure the casing surrounding the boiler is sectioned to show the generating-tubes and the headers.

The header which forms the subject-matter of my invention is a tube, of wrought-iron or 55 mild steel, having at its upper end a cylindrical portion below which and opposite the ends of the generating-tubes the header is flattened, so as to form flat surfaces in which are holes for the reception of the ends of the 60 generating-tubes and for the hand-holes, by which access is gained to the generating-tubes. These headers are formed from tubing of standard size by cutting the tubing into proper length and flattening that portion of 65 each blank so formed which is to receive the ends of the generating-tubes, so as to give it an oval or rectangular section, as shown in Fig. 6. In the flat surfaces so formed holes for the reception of the generating-tubes and 70 the opposite hand-holes may be bored and the tubes extended into the header, which would be impossible were the header to retain its cylindrical form where it is connected to the generating-tubes. The tube may be flattened 75 in the manner described by hammering and without the use of tools other than those which are always found in boiler-shops.

Heretofore in forming wrought-iron or steel headers it has been the custom to form these 80 headers by successive welding operations and by the use of collapsible dies. This method of construction is difficult to carry out, and the headers so made have been expensive.

By my invention the headers may be made 85 easily and cheaply, and, as above stated, no special tools, such as collapsible dies, are required.

Referring now to the drawings and at first to Figs. 1 to 6, inclusive, 1 1 are the steam 90 and water drums of the boiler, suspended in the brick setting of the furnace-chamber of the boiler. In the bottoms of these drums are boxes or saddles 2 2, from which depend head-

ers 3 3, constructed in accordance with my invention. These headers are at both the front and the rear of the drums. The front and rear headers are connected by rows of inclined generating-tubes 4 4 within the furnace-chamber of the boiler.

5 5 are the grate-bars of the furnace, and 6 and 7 are deflector-plates over the furnace, the object of which is to cause the gases from 10 the furnace to follow a sinuous course in passing around the generating-tubes, so as to pass over as much surface of these tubes as possible and to impart as much heat as possible thereto. These deflecting-plates are parallel 15 with and may be supported by the generating-tubes. Their ends overlap for a considerable distance, so that in passing around the plates the furnace-gases must pass over practically the whole length of the generating-20 tubes.

In order to prevent the furnace-gases from entering the stack through the crevices between the rear headers without first passing between the deflector-plates 6 and 7, the rear 25 headers may be luted with luting material below the plate 7.

The headers are shown in detail in Figs. 1 to 6, inclusive. Each header, as shown in the general views and in Fig. 3, consists of a 30 tube having an upper cylindrical portion, the section of which is shown in Fig. 5, and which tapers into a lower rectangular portion, the section of which is shown in Fig. 6, and which is formed, as already explained, by flattening 35 a portion of the generating-tube from which the header is formed. In one side of this rectangular portion of the header are bored holes into which the ends of the generating-tubes may be expanded. On the opposite 40 side of the header are similar holes, forming hand-holes, by which access may be gained to the generating-tubes for the purpose of examining, cleaning, removing, and renewing the generating-tubes. The end of 45 each header is closed at the bottom by a cap 8.

Since the upper ends of the headers are cylindrical, they may be expanded directly into the saddles 2 2 without the use of connecting-nipples. This construction, therefore, reduces the number of expanded joints

in the boiler and the number of parts and greatly strengthens it. The headers are arranged close together within the boiler, as shown in Fig. 2, and little space is left between them for the passage of gases. 55

In Fig. 7 is shown a type of boiler more particularly adapted for marine use and employing headers likewise constructed in accordance with my invention. In this type of 60 boiler the generating-tubes run diagonally across the furnace-chamber and are arranged in two oppositely-inclined series. The headers are formed, as in the first form of boiler, from tubing flattened at those portions which 65 receive the generating-tubes, and these headers are bent substantially at right angles, so that each header receives at its lower end the ends of generating-tubes of one series and at its upper end the ends of generating-tubes of 70 the other series.

The headers of the boiler shown in Fig. 7 are provided with hand-holes both at the top and bottom, through which the generating-tubes may be cleaned and examined. 75

Having thus completely described my invention, what I claim, and desire to secure by Letters Patent, is—

1. The herein-described header for sectional boilers, consisting of a wrought-metal 80 tube, round at one end for insertion into the steam and water drum, and closed at the other end, and flattened for a portion of its length and having in its flattened portion holes for the reception of the generating-tubes, substantially as described.

2. In a sectional boiler, the combination, with a steam and water drum, of generating-tubes below said drum, and headers connecting the ends of said generating-tubes with the 90 steam and water drum, formed of metal tubing, flattened for a portion of their length and having in such flattened portions holes for the reception of the ends of the generating-tubes, and expanded into holes in said steam 95 and water drum, substantially as described.

In testimony whereof I affix my signature in presence of two witnesses.

ROLLA C. CARPENTER.
